(57) **CLAIM**

The ornamental design for a bottle, as shown and described.

DESCRIPTION

FIG. 1 is a top perspective view of the first embodiment of the bottle showing my new design;

FIG. 2 is a bottom perspective view of the bottle of FIG. 1;

FIG. 3 is a top plan view of the bottle in FIG. 1;

FIG. 4 is a side elevational view of the bottle of FIG. 1;

FIG. 5 is a bottom plan view of the bottle in FIG. 1;

FIG. 6 is a top perspective view of the second embodiment of the bottle showing my new design.

FIG. 7 is a bottom perspective view of the bottle of FIG. 6;

FIG. 8 is a top plan view of the bottle in FIG. 6;

FIG. 9 is a side elevational view of the bottle of FIG. 6; and,

FIG. 10 is a bottom plan view of the bottle in FIG. 6.

The broken lines shown are for the purpose of illustrating portions of the bottle that form no part of the claimed design.
